EDGE BINDING FOR SHOE UPPERS

Maynard Hale Moore, Jr., Everett, Mass.

Application January 8, 1937, Serial No. 119,592

1 Claim. (Cl. 36—57)

This invention relates to certain improvements in ornamental binding for the edges of shoe uppers and more particularly to that type of binding known as "French cord", in which a strip of leather is stitched to the upper close to the edge, with the grain side of the strip laid against the grain side of the upper and their edges in coincidence, the strip then being bent over the edge of the upper and cemented to its inner side, with the result that the effect of a corded or beaded edge is produced on the edge of the upper.

The object of the present invention is to produce what may be termed a double French cord edge, in that the effect of a double corded edge may be produced in different colors, for the purpose of securing a novel and ornamental appearance when a two color effect is desired.

I accomplish this object by producing a binding strip which comprises a main strip of leather or imitation leather of a width corresponding to that usually employed in providing an ordinary French cord edge, and by attaching, preferably by stitching, a longitudinally folded strip of leather, or imitation leather, of a contrasting color, to the grain side of the main strip with the edges of the folded strip in coincidence with one edge of the main strip and then attaching the combined strips to the upper close to its edge by a row of stitches which are placed closely adjacent the edges of the two strips, the subsequent steps of operation being the same as with the formation of the ordinary French cord binding.

For a more complete disclosure of my invention reference is now made to the following specification, in connection with the accompanying drawing in which:

Fig. 1 is a combined cross-sectional and perspective view of a binding strip embodying my invention.

Fig. 2 is a similar view, illustrating a preliminary step in the attaching operation.

Fig. 3 is a similar view illustrating the completion of the operation.

Fig. 4 is a side view illustrating the outer side of the binding strip when applied.

According to my invention I provide a main strip of leather, or imitation leather, *a*, of a width corresponding to the width of the strip usually employed in forming a French cord binding, and a supplemental strip *b*, also of leather, or imitation leather, which is folded lengthwise at its middle about a cord *c*, with its grain or finished side out, and is attached by stitches *d* to the grain or finished side of the strip *a* with

the edges of the folded strip flush with one of the edges of the main strip, as shown in Fig. 1. The folded strip may be adhesively attached to the main strip, but attachment by stitches is considered preferable, as it is less expensive.

In attaching the combined strips to the edge portion of an upper section, as *e*, the folded strip *b* is laid against the grain, or outer side of the upper, so that the edges of the strips and upper are approximately in coincidence, and the strips are attached to the upper by a row of stitches *f*, which are placed close to the coincident edges of the strips, as shown in Fig. 2. The main strip *a* is then folded over the edge of the upper and pressed against and cemented to its flesh side, as shown in Fig. 3. A quick setting adhesive may be employed in lieu of the stitches *f*, but the latter are considered preferable.

In practice the main strip *a* and folded or supplemental strip *b* will be made from leathers, or imitation leathers having their grain or outer surfaces finished in different colors and, when the operation is finished, the portion of the strip *a*, which extends over the edge of the upper, and the rounded, or beaded portion of the strip *b*, which is folded about the cord *c*, will both be visible and thereby an attractive ornamental effect is produced, the edge of the upper thus being trimmed with two parallel strips of different colored leather, as indicated in Fig. 4.

The attaching operation is performed in the same way as the ordinary French cord binding, without increased labor cost, the only substantial increase in cost being in the factory of the producer of the binding. The binding may be employed in any edge portion of a shoe where a two color, ornamental effect is desired.

I claim:

In combination with the edge portion of a shoe upper, a binding strip comprising a main strip portion, and a relatively narrow supplemental strip portion folded along its middle longitudinally with its finished side out and attached to the finished side of the main strip with its edges in substantial coincidence with one edge thereof, said supplemental strip being positioned against the outer side of the upper with its edges in approximate coincidence with the edge thereof and being attached thereto by stitches which extend through both portions of the binding strip, said main strip being bent over the edge of the upper and being secured to the inner side thereof, so that both portions of the binding strip are exposed.

MAYNARD HALE MOORE, JR. 55
